UNITED STATES PATENT OFFICE.

SIDNEY VOLK, OF BENTON HARBOR, MICHIGAN.

TUBULAR-RADIATOR CONSTRUCTION.

1,391,871.

Specification of Letters Patent. Patented Sept. 27, 1921.

Application filed May 26, 1919. Serial No. 299,807.

To all whom it may concern:

Be it known that I, SIDNEY VOLK, a citizen of Russia, and a resident of Benton Harbor, Michigan, have invented a certain 5 new and useful Improvement in Tubular-Radiator Construction, of which the following is a specification.

This invention relates to the construction 10 of radiators for internal combustion engines such as those employed on automobiles, or in any apparatus in which a radiator is necessary for cooling the water of a circulating system, or for any similar purpose.

Generally stated, the object of the invention 15 is to provide an improved construction and arrangement whereby the tubes of the radiator are each individually removable without the necessity of disturbing any of the other tubes adjacent thereto.

20 It is also an object to provide an improved construction and arrangement which will prevent injury to the radiator in the event that the water therein becomes cold enough to freeze.

25 It is also an object to provide certain details and features of construction and combinations tending to increase the general efficiency and the desirability of a tubular radiator of this particular character.

30 To these and other useful ends the invention consists in matters hereinafter set forth and claimed, and shown in the accompanying drawings in which—

Figure 1 is a side elevation of a plurality 35 of radiator tubes involving the principles of the invention, showing one of said tubes partially withdrawn from between the others.

Fig. 2 is a front elevation of a section of a tubular radiator constructed in accordance 40 with the principles of the invention.

Fig. 3 is an enlarged detail view showing a portion of the front of the radiator.

Fig. 4 is an enlarged longitudinal section through a portion of the radiator.

45 Fig. 5 is a cross section on line 5—5 in Fig. 4.

Fig. 6 is a cross section on line 6—6 in Fig. 4.

As thus illustrated, the radiator is constructed 50 from a plurality of tubes extending parallel with each other, and as the tubes are all of the same formation and construction, a description of one will be sufficient. As shown, therefore, each tube comprises 55 a middle portion 1 which is preferably corrugated in the manner shown more clearly

in Fig. 6. The square heads 2 of the tube are much larger in cross section than the corrugated middle portion of the tube, and are united to said middle portion by tapered portions 3, so that each tube comprises a relatively small middle portion provided at its opposite ends with relatively large square heads. The sheet metal from which these tubes are formed is preferably turned back within each square head 2 to form an inside reinforce 4, thus strengthening the heads of the tubes. In assembling the tubes, they are laid up, for example, in the manner shown in the drawings, in vertical and horizontal rows, but with space between the opposing flat sides of the heads 2, and within these spaces solder 5 is provided to seal the front and rear sides of the radiator, so that the water cannot escape between the tubes. It will be understood, of course, that the radiator is suitably incased, so that the water is confined in the spaces between the middle portions 1 of the tubes, and is free to circulate between the 80 tubes while the opposite ends of the tubes are left open to allow the air to pass through from one end to the other for the purpose of radiating the heat and cooling the water. With the provision of the longitudinal corrugations 6 on the inner surface of the middle portion of each tube, it will be seen that the tubes will submit to a considerable external pressure if the water freezes, without being crushed, inasmuch as each tube is 90 adapted to contract somewhat under the pressure.

Now, should any of the tubes become damaged, or should it be necessary to remove them for any other reason, it will be 95 seen that any particular tube can be easily removed without disturbing the others adjacent thereto. This may be done by melting the solder 5 around the head of the particular tube to be removed, and when this 100 is done, an instrument can be inserted to pull or push the tube out, this being easily accomplished because of the fact that the openings or spaces in which the square heads of the tube to be removed are held are each 105 a little larger than the square head itself, and are much larger than the middle portion of the tube. Furthermore, there is nothing to catch when it is attempted to pull out the tube, for the tubes are smooth and free from 110 edges or projections which might cause trouble of this kind, each square head being

- joined to the middle portion of the tube by a tapered portion 3, as described, which permits the rear end of the tube, when it is pulled forward endwise, to slide out through the opening left by the front end of the tube, regardless of in which direction the tubes are pushed out. The solder which is run into the spaces between the heads of the tubes may entirely fill these spaces, or may be restricted to the outer portions of these spaces, so that only the extreme outer edge portions of the tubes are soldered together, thereby making it easier to melt the solder when it is desired to remove any of the tubes. The flame of a torch, for example, directed against the outer edges of the thin layers of solder, or even directly into the mouth of the tube itself, will obviously be sufficient to melt the solder around the particular tube which it is desired to render removable by the melting of the solder. The tubes can be made of sheet metal of any suitable character, such as that ordinarily employed for this purpose. Preferably when made of copper, the tubes are first given a bath in melted solder, to give them a coating. In assembling the tubes, they are then bound together in the desired relation, somewhat tightly at one side of the radiator than at the other, so that the ends will not be exactly tight together at the other side. The face of the radiator is then pressed downwardly into a tub of melted solder, so that the latter will creep in between the ends of the tubes which are not held so tightly together, thus not only melting the previously formed solder coating on the square heads or ends of the tubes, but also filling any gaps or small spaces which may exist between the flat sides of the square heads of the tubes. This completely binds the tubes together and seals the spaces between either the front or the rear side of the radiator, and then the cords or wires or other binding are removed to allow the ends of the tubes at the other side to spring very slightly apart, and this side of the radiator is then forced downwardly into a body of melted solder, and the tubes at this side of the radiator will be soldered together in the manner previously described. Thereafter, of course, as previously stated, a suitable casing is placed around the radiator, so that the water will be confined in the spaces between the tubes. Thus, with this construction, the flame of a torch when directed into the open end of a tube will not only melt the solder around this end of the tube, so as to loosen the square head of the tube, but will also melt the solder around the other end of the same tube, inasmuch as the flame and heat will pass entirely through the tube, thus loosening both ends of the tube at the same time. Then, by using a pair of pliers or other tool, the loosened tube can be pulled outward, and the reinforce in the end of the tube will tend to prevent the tool from injuring the sheet metal of the tube, or from distorting the end of the tube, which is one of the objects of the reinforce previously described. In forming the tubes, it is found that the contraction of the middle portion of the tube, by forming the longitudinal corrugations, so that the tube becomes of less diameter, serves to form the tapered portions 3, as it is here that the corrugations terminate or disappear, each corrugation preferably having a tapered end, but these ends terminate short of the flat surfaces which form the sides of the square heads of each tube.
- Thus each tube is externally smooth and free from edges or projections which might interfere with the insertion and removal of the tubes, and each tube is internally reinforced at each end thereof, so that the two heads of the radiators, each head being made up of the square ends of the tubes, are very strong and rigid and adapted to withstand the expansion and contraction due to changes in temperature, as well as other strains, and whereby each tube is individually removable endwise, in the manner specified.
- By providing the internal reinforcements 4 the rectangular heads of the tubes are rendered noncompressible, so that the compressible metal portion 1 of each tube terminates at each end in a noncompressible head. In other words, the in-turned portions 4 prevent the compression of the tube, which might occur in case of freezing, from extending into the heads, as the inner edge of each portion 4 is in position to prevent the compression from extending from the tapered portion 3 into the rectangular head, whereby such compression will not tend to distort the rectangular heads in a way that might loosen the connections between the heads, or in a way that might tend to produce trouble or difficulty in the removal and subsequent reinsertion of any of the tubes.
- What I claim as my invention is:—
1. In a radiator, a plurality of parallel sheet metal tubes formed with reduced middle portions to provide spaces between them for the circulation of the water and having rectangular heads which are externally smooth and internally reinforced and which are held together by solder which seals the spaces to prevent leakage of the water and to render each tube removable endwise without disturbing the others adjacent thereto.
  2. A radiator structure as specified in claim 1, said reduced middle portion of each tube being connected by short portions tapering therefrom to the rectangular heads.
  3. A radiator structure as specified in claim 1, each tube being turned in at oppo-

site ends thereof to form the said reinforce inside of each head.

4. A radiator structure as specified in claim 1, the middle portion of each tube being corrugated longitudinally inside to reduce the diameter and render the tube compressible between said non-compressible internally reinforced heads in case the water freezes within the radiator, having tapered portions between said heads and the middle portion, and said corrugations extending into said tapered portions and stopping short of the reinforce in said heads.
5. A radiator structure as specified in

claim 1, the sides of each rectangular head 15 being all disposed outside of the external diameter of said middle portion.

6. A radiator tube having a reduced middle portion 1, square heads 2 the sides of which are outside of the external diameter 20 of said middle portion, tapered portions 3 to unite the middle portion with said heads, and in-turned portions 4 forming a lining for the entire interior of said square heads, providing a compressible middle portion 25 between non-compressible heads.
